UNITED STATES PATENT OFFICE.

MAX HECHT, OF NEW YORK, N. Y.

DESIGN FOR A SMOKING-SET.

SPECIFICATION forming part of Design No. 17,741, dated September 27, 1887.

Application filed July 14, 1887. Serial No. 244,356. Term of patent 3½ years.

To all whom it may concern:

Be it known that I, MAX HECHT, a citizen of the United States, residing in the city, county, and State of New York, have invented 5 and produced a new and original Design for a Smoking-Set, of which the following is a specification.

Reference is to be had to the accompanying drawing, forming a part of this specification, 10 in which the figure is a front elevation of my newly-designed smoking-set.

The leading feature of my design consists in a smoking-set in imitation of pair of cuffs and a necktie.

15 A represents the cigar-receptacles, made in the form of cuffs. Between these appears the piece B. This is in the form of a necktie and set at an angle. In front of the center piece, B, is placed the ash-receptacle C, also in the form 20 of a cuff. The whole is mounted upon a base, D. The parts are provided with protuberances *a* and *b*, in imitation of cuff and sleeve buttons, and the corners *f* are opened and made triangular. The part C is provided with a

protuberance, *h*, in imitation of a cuff-button, 25 and the corners *i* thereof are opened and made triangular. The center piece, B, shows the crossed plates *k* and the central triangular piece, *k'*, in which appears the protuberance *m*, in imitation of a scarf-pin, and spaces *n n* 30 appear between the edges of the center pieces and the side pieces, A. The whole presents to the eye the appearance of cuffs and scarf mounted together.

I claim—

1. The design for a smoking-set herein shown and described, the same consisting of the cylindrical side receptacles, A, and the intermediate piece, B, in the form of a necktie. 35
2. The design for a smoking-set herein shown and described, the same consisting of the side cylindrical receptacles, A, the center piece, B, in the form of a necktie, and the front cylindrical piece, C. 40

MAX HECHT.
